UNITED STATES PATENT OFFICE.

ALBERT WILLIAM GUSTAFSON, OF JERSEY CITY, NEW JERSEY.

ENGINE-CYLINDER.

1,105,423.

Specification of Letters Patent. Patented July 28, 1914.

Application filed September 24, 1912. Serial No. 722,022.

To all whom it may concern:

Be it known that I, ALBERT WILLIAM GUSTAFSON, a citizen of the United States, and a resident of Jersey City, in the county of Hudson and State of New Jersey, have invented a new and Improved Engine-Cylinder, of which the following is a full, clear, and exact description.

Among the principal objects which the present invention has in view are: to prevent loss of heat in the expansive medium employed by the engine; to automatically create and maintain a jacket of rarefied air surrounding the chambers containing the expansive medium; and to simplify the construction of the apparatus whereby the above-stated objects are obtained.

Reference is to be had to the accompanying drawings forming a part of this specification, in which similar characters of reference indicate corresponding parts in all the views.

Figure 1 is a longitudinal vertical section of a steam cylinder and chest therefor, taken on the line 1—1 of Fig. 3, and showing in conjunction therewith a locomotive boiler and supporting saddle therefor; Fig. 2 is a horizontal section of the steam chest, taken on the line 2—2 in Fig. 3; Fig. 3 is a vertical cross section, taken on the line 3—3 of Fig. 1; and Fig. 4 is a detail view showing in elevation one of the spool heads of the piston valve employed in conjunction with the present invention, and a section of the tubular form of the piston rod used therewith.

As seen in the accompanying drawings, the steam chest 9 and the cylinder 10 are infolded by an annular space 11 which in the operation of the invention serves as a jacket for the said chamber and cylinder. The width of the jacket 11 is optional, depending on the taste or desires of the designer or owner. The jacket 11 is connected with the suction chamber 12 by passages at both sides 45 of the partition plate 14.

The plate 14 is centrally provided with a boss 15 which is bored to provide the runway 16 for the tubular section 17 of the valve piston rod 18. It is upon the section 50 17 that the heads 19 forming the spool valve are mounted. The section 17 is also supported in a runway 20 formed in the boss 21. The borings of the bosses 15 and 21 are co-axial. It is preferred to construct the 55 section 17 integral with the heads 19, and, where the design admits, with the rod 18.

The boss 21 is projected from the inner face of the head 22 of the steam chest 9. The usual packing gland 23 is employed on the head 22 through which the rod 18 extends. 60

The section 17 is made hollow and opened at one end to provide an outlet for the exhaust steam or gases. For this purpose the ends of the tube are provided with passages 24, said passages being so disposed as to pass within the bosses 15 and 21 respectively and alternately. When the said passages are drawn without the said bosses they open communication with the steam chest and the tube 17. The tube 17 then acts as a duct 70 for the exhausting medium, delivering the same through the passage 25 in the chest head 26 to the exhaust pipe 27, which then conveys the steam or gas to the exhaust nozzle 28 (see Fig. 3).

By the operation of the spool valve having heads 19, the steam supply duct 29 is alternately placed in communication with the ducts 30 leading to the ports 31 of the cylinder 10. Simultaneous with the exposure of either one of the ducts 30 to the duct 29, the other one of the said ducts is exposed to the chamber of the steam chest 9 to exhaust therethrough from the expanded side of the cylinder 10. The movement of the head 19 of the steam chest valve to open the duct 30 to the chest withdraws the section 17 from the bosses 15 or 21, as the case may be, to open communication between the exhausting portion of the steam chest to the 90 exhaust pipe 27.

I employ the rush of the escaping exhaust steam or expansive medium to establish and maintain a rarefied atmosphere or partial vacuum in the jacket 11. This is accomplished by limiting the passage 16 to provide a space between the end of the same and the interior end of the boss having the passage 25 of the head 26. The end of the passage 25 is flared, as seen best in Fig. 1 100 of the drawings, to form a bell mouth 32 to receive the conical outer end of the casting forming the partition 14 and boss 15. The cap or space between the conical end of said casting and the bell mouth 32 of the 105 passage 25 constitutes an ejector which operates to form a suction in the passage between the conical end and bell mouth, operating to draw from the suction chamber 12 the expansive medium or gas therein. 110 Said chamber being in direct communication with the jacket 11 operates to withdraw

- gas and air from said chamber, rendering the atmosphere rarefied or furnishing a partial vacuum within said chamber. The inner wall and outer wall of the jacket 11 being thus separated, and the atmosphere of the intervening space being rarefied, the heat transmission from the inner to the outer wall is negligible. Further, the rarefaction of the atmosphere within the jacket 10 11 materially avoids transmission from the inner wall of the cylinder and steam chest, and thus conserves the heat of the said inner wall and the medium within the said cylinder and chest.
- 15 It is readily understood that as the piston valve is operated by the links, the steam is admitted successively to opposite sides of the piston 33 and to the opposite ends of the cylinder 10, to be exhausted from the dead 20 steam side of the piston to the chest 9 and from the same through the tube 17 to maintain a constant suction at the cap between the passages 16 and 25 to draw the atmosphere from the suction chamber 12 and the jacket 11. In this manner a constant de-

gree of rarefaction is maintained in the jacket 11, insulating thereby the chest 9 and cylinder 10 from the surrounding atmosphere.

Having thus described my invention, I 30 claim as new and desire to secure by Letters Patent:

In combination with an engine cylinder having a hollow wall to form an air jacket for said cylinder; a reciprocating valve; a 35 hollow valve rod having an opening to receive the exhaust from said cylinder; an exhaust pipe spaced apart from said valve rod to form an injector gap; and a chamber surrounding said gap in open communication with the air space surrounding said cylinder.

In testimony whereof, I have signed my name to this specification in the presence of two subscribing witnesses.

ALBERT WILLIAM GUSTAFSON.
